UNITED STATES PATENT OFFICE.

BERNARD VAN LEER, OF AMSTERDAM, NETHERLANDS.

CLOSURE FOR VESSELS AND DEVICE FOR SEALING THE SAME.

Application filed March 30, 1920. Serial No. 370,042.

To all whom it may concern:

Be it known that BERNARD VAN LEER, subject of the Queen of the Netherlands, residing at Amsterdam, Kingdom of the Netherlands, has invented certain new and useful Improvements in Closures for Vessels and Devices for Sealing the Same, of which the following is a specification.

This invention relates to closures for vessels containing petrol, dyestuffs or other liquids and to devices for sealing the same and has particular reference to that class of closure which comprises a cap screwed on to the neck of the vessel.

In the known closures of this kind there are arranged at the top of the screw cap two projections, lying diametrically opposite to one another, both of which are bored horizontally; there is also provided on the side 20 of the neck of these vessels a lug which is similarly bored.

For the purpose of sealing these known closures a cord or a metal wire is drawn through one or through both of the horizontal bores provided on the screw cap, and also through the lug arranged on the neck of the vessel, after which the ends of the cord or of the metal wire are passed between two little sealing plates or sealing strips and fastened together by means of pliers.

In large works, particularly in large petrol warehouses where thousands of vessels are sealed daily, this sealing needs a large expenditure of time, and this is naturally a defect.

A further disadvantage of these known closures consists in the fact that the projections, lying diametrically opposite to one another, which are arranged on the screw cap do not afford an adequate security against opening of the closure.

For if after removal of the seal the projecting rim, usual for example in petrol containers of the bottom of a second petrol vessel, is placed on the vessel to be opened in such a manner that the lateral surface of the one projection presses against the outside of the above mentioned projecting rim, and the lateral surface of the second projection against the inside of the same, and if the second petrol container provided with this projection rim is thereupon turned, then these vessels of older construction can be opened without difficulty. By opening in this way, which is largely employed, the

petrol vessels used for the purpose are to a large extent worn out, they are considerably bruised, made leaky and otherwise damaged, so that in a short time they become unsuitable for any further use.

The present invention is intended to overcome these disadvantages.

The characteristic feature of the invention consists in the fact that by the arrangement of a suitable number of slots or openings in flanges or rims, which are arranged on the one hand on the screw cap and on the other hand on the neck of the vessel, and which flanges or rims may be either circular or segmental or of any other form, there are provided a number of slots or other openings which on screwing the cap on to the neck of the vessel come to lie more or less one above the other.

The purpose which is thereby achieved is that these slots always come one above the other in such a manner that in every position of the screw cap on the neck they more or less cover one another and enable the sealing means which may consist of a cord capable of being sealed with lead or of a metal strip or other similar device, to be drawn through.

A further characteristic feature of the invention consists in the fact that the sealing of the screw cap on to the neck of the vessel by means of these slots or other openings provided in the flanges or rims can be effected not only by cords capable of being sealed with lead, but by metallic strips which in themselves form the sealing device.

A third characteristic feature of the invention consists in the fact that there are provided both on the screw cap and on the neck of the vessel laterally projecting rims or flanges, provided with slots, in which these slots are so arranged that in every position of the screw cap the slot which is arranged in the laterally projecting rim of the screw cap adjusts itself wholly or in part vertically above the slot which is situated in the rim provided on the neck of the vessel.

This may be effected by providing slots of about equal size in both rims, but making the separation of the slots from one another in the one rim different to the mutual separation of the slots in the second rim.

By the arrangement of the laterally projecting rims there is achieved by the present invention the advantage that the pro-

jections arranged on the screw cap are dispensed with and can be replaced by a single projection which is given a triangular, square or other shape so that the screw cap 5 can only be opened by means of a suitable tool.

It is not necessary that the screw cap and the neck of the vessel should have rims running all the way round, and it is sufficient if for example a rim running all the way round is provided on the neck only, and if a rim is arranged on the screw cap 10 extending along a portion only of its circumference, or vice versa if a segmental rim 15 is provided on the neck and a rim running all the way round on the screw cap.

The number of slots provided on both these rims may be as many as desired. The slots must, however, be so adjusted one 20 above the other that they leave sufficient room between them to allow of the insertion of the sealing device.

The construction may be carried out in such a manner that in the rim of the screw 25 cap for example there are provided only three slots.

One of the forms of construction in which this apparatus can be constructed consists in arranging in one of the rims, for example 30 in that of the screw cap, three slots the length of which is equal to that of the slots in the rim of the neck of the vessel, and which are also of the same length as the distance which separates the individual 35 slots in the rim of the neck of the vessel one from another.

On the other hand in the above mentioned form of construction the distance between the slots in the rim of the screw cap amounts 40 to one quarter of the length of the slots.

If now the screw cap is screwed on to the neck, there is formed, in consequence of the difference in these distances between the slots in the two rims, a space serving for the 45 insertion of the fastening or sealing cord which amounts to at least about five-eighths of the length of the slots.

These forms of construction can naturally be constructed in any other desired dimensions.

For the purpose of sealing the fastening, the cord or the metal wire is according to the present invention drawn through two openings only, very conveniently situated in 55 relation to one another. These openings can, by a suitable choice of the length of the slots, be enlarged to any desired extent. Further, by arranging the laterally projecting rims in such a manner that the one is situated on the 60 under side of the screw cap and the second on the upper side of the neck immediately below the portion of the neck provided with a screw thread, the openings can be brought so near to one another that to a certain extent 65 they form only one opening.

A further improvement of the apparatus according to the present invention consists in the fact that in consequence of the oblong formation of the openings the cord or metal wire employed for sealing the fastening, can 70 be replaced by a metallic strip. This strip can be formed in such a manner that its ends can at the same time be employed as little plates which are for this purpose pressed together and fastened by means of pliers. 75 In consequence of this arrangement the inconvenient introduction of the ends of the cord or of the metal wire between the little sealing plates is also dispensed with, and the employment of the heavy lead sealing pliers 80 is also avoided.

The ends of the metallic strip can for example also be formed as the two portions of a press-stud; in this case these two ends can be fastened together and pressed against 85 the neck of the vessel by pressing the press-stud flat by means of pliers gripping round the neck of the vessel.

In the accompanying drawing is illustrated a closure of the old type and a form 90 of construction, given by way of example, of the closure according to the present invention and there is shown in:

Figure 1 a side view and in

Figure 2 a view from above of the sealable 95 closure according to the known constructions;

Figure 3 illustrates a side view of the closure according to the present invention;

Figure 4 is a view from above of the screw 100 cap and Figure 5 a view from above of the neck of the vessel;

Figure 6 illustrates a vertical section through the closure to be sealed in accordance with the present invention.

Figure 7 shows a view from above and Figure 8 a side view of the metal strip used according to the present invention and serving as a seal.

Figure 9 shows on an enlarged scale a side 110 view of a metal strip, serving as a seal, the ends of which on being fastened together are at the same time pressed against the neck of the vessel.

In the closure of the older type (Figures 115 1 and 2) 1 is the neck, which is arranged on the vessel and is provided with a lug 2 with horizontal bore 6; a is the screw cap which is screwed on to the neck and carries projections 4 in which are provided horizontal 120 bores 5.

In the closure according to the present invention (Figures 3 to 6) there is provided on the neck a rim 7, running all the way round, which is furnished with slots 9; the screw 125 cap 3 carries a square projection 11 and is on a portion of its circumference furnished with a rim 8 provided with slots 10.

After the screw cap 3 has been screwed as far as possible on to the neck and tightened 130

up, the end 13 of the metal strip 12 (Figures 7 and 8) is drawn through the slots 9 and 10 situated vertically one above the other, which then to a certain extent form a single opening. The strip 12 is then bent downwards in such a manner that for example the projecting edges 15 of the end 14 catch round the end 13. The end 13 is then by means of a suitable tool by the help for example of pliers gripping round the neck of the vessel, enclosed in the end 14 by bending over the edges 15 and the end 14 is pressed against the neck 1.

In the form of construction of the seal illustrated in Figure 9 the metal strip 16 serving as seal is formed in the shape of a stirrup and is provided at its ends with two protuberances 17 and 18 lying one within the other. After this metal strip has been drawn through the slots 9 and 10, the protuberances 17 and 18 are by means of pliers gripping round the neck 1 pressed flat, in such a manner that they form two folds lying one within the other, which are at the same time pressed against the neck 1.

After the breaking of the seal the screw cap can only be unscrewed by the help of a tool engaging with the projection 11. Any kind of metal seal can be employed, for example lead sealing, or metal strips pressed one into the other by a tool, or the like.

Having now particularly described and ascertained the nature of my said invention, and in what manner the same is to be performed, I declare that what I claim is:

1. A closure provided with a seal, for vessels of every kind characterized by the arrangement of a suitable differently spaced number of slots or openings in flanges or rims which are arranged on the one hand on the screw cap and on the other hand on the neck of the vessel in such a manner that, on screwing the cap on to the neck of the vessel, these slots are so adjusted one against the other, that in every position of the screw cap on the neck a pair of slots are substantially superposed one over the other and enable the sealing device (metal strip or the like) to be drawn through.

2. A form of construction of the closure in accordance with claim 1 the feature of which is that the neck (1) has a laterally projecting rim (7), running all the way round, while the screw cap is provided with a laterally projecting rim (8) round a part only of its circumference, substantially as and for the purpose set forth.

3. A form of construction of the apparatus in accordance with claim 2 the feature of

which is that the rim (7) of the neck (1) of the vessel is provided with slots (9) which are of the same size as the distance between these slots one from another and a further feature of which is that the slots (10) arranged in the rim (8) of the screw cap (3) are of the same size as the slots (9) situated in the rim of the neck of the vessel, but that the distance between the slots (10) arranged in the screw cap, one from another is less than that of the slots (9) one from another, in order that on screwing the screw cap (3) on to the neck (1) of the vessel there may be formed by the superimposition of the openings of the slots 9 and 10 such slot spaces as are sufficient to permit the passage of the sealing cord or of the sealing plate.

4. A form of construction of the apparatus in accordance with claim 3 the feature of which is that the rim of the screw cap (3) is provided with three slots, which are of the same length as the slots (9) which are situated in the rim (7) arranged on the neck (1) of the vessel, and of the same size as the distances at which these slots are situated one from another, and a further feature of which is that the slots (10) in the rim (8) arranged on the screw cap (3) are at a distance from each other the length of which amounts to about one quarter of the length of the slots situated in the screw cap.

5. A form of construction of the apparatus in accordance with claim 4 the feature of which is that the laterally projecting rim 8 is arranged at the foot of the screw cap, and the laterally projecting rim 7 at the uppermost end of the neck of the vessel, the latter being, however, immediately below the screw thread (19) of the neck (1) of the vessel.

6. A form of construction of the apparatus in accordance with claim 5, the feature of which is that the sealing is effected by a metal strip which is put through the slots 9 and 10, for which its two ends are pressed tight one against the other.

7. A form of construction of the apparatus in accordance with claim 6, the feature of which is that the ends of the metal strip are provided with protuberances, extending from one side of the strip to the other and fitting one into the other which, in the production of the seal, are transformed into folds lying one within the other.

In testimony whereof he affixed his signature in presence of two witnesses.

BERNARD VAN LEER.
